UNITED STATES PATENT OFFICE.

GASTON JOURDAIN, OF PARIS, FRANCE.

WARPERS' CREEL.

1,427,394.

Specification of Letters Patent. Patented Aug. 29, 1922.

Application filed June 1, 1921. Serial No. 474,104.

To all whom it may concern:

Be it known that I, GASTON JOURDAIN, citizen of the French Republic, residing at Paris, in the Department of Seine and State 5 of France, have invented certain new and useful Improvements in Warpers' Creels, of which the following is a specification.

This invention relates to warpers' creels and has for its object a creel which whilst allowing of a very high speed of operation with a minimum of broken ends and without increase of labour, thus increasing production, will occupy less space than those at present in use and will permit of the warping frame and the creel being placed more closely together than at present, thus lessening the length of yarn between the unwinding point and the point where the yarn is wound upon the beam. The invention relates particularly to creels for the reception of warp cops, cheeses, or any other form in which yarn is wound, hereinafter for convenience referred to as a cop, but is also applicable for use with flanged warpers' bob- 25 bins.

In carrying the invention into effect I provide a half cylinder which comprises the creel proper, this half cylinder having mounted on its inner face spindles adapted 30 to receive the cops to be wound upon the beam. A comb is fitted parallel to and in the plane of the longitudinal axis of the half cylinder, and all the yarns from the cops are led through the teeth of this comb and 35 thence to the beaming frame. It follows from this construction that the length of yarn from each cop is the same as another the cops are unwound in a direction parallel to their longitudinal axis, and equal tension 40 of the yarn throughout the beaming operation, with a minimum of resistance to unwinding of the yarn from the cops, is obtained.

The invention will be fully described with 45 reference to the accompanying drawings, wherein:—

Figure 1 is a diagrammatic view in side elevation of a creel constructed according to my invention.

50 Figure 2 is a similar view in plan.

Figure 3 is a side elevation of a creel showing in a detailed manner how the invention is carried into effect.

Figure 4 is a plan showing a preferred

arrangement in staggered relation of rows 55 of cop-carrying spindles, and

Figure 5 is a detail of yarn guiding means.

In Figures 1 and 2, it will be seen that in principle the creel is comprised of a support 1 of semi-cylindrical form, which support 60 may be of any convenient material, such as wood, sheet metal, etc., arranged in relation to the floor in such a manner that its axis may be parallel thereto, that is to say, horizontal, the side 2 nearest the warping 65 frame being below the level of the axis, and the side 3 being on the contrary above the level of said axis. The position of the half-cylinder 1 may be maintained in any convenient manner as for instance by the feet 4. 70

On the inner face of the part 1 are arranged in any convenient manner, preferably in staggered rows as shown in Figure 4, short spindles 5, the axis of which coincide with radii of the half cylinder 1, these spindles 75 5 being secured on the inner curved face of the part 1 in any convenient manner. They may or may not be spring mounted thereon. Their purpose is to receive the cops 6 of which the yarns 7, being unwound in a direction parallel to the axis of the cop, form the fleece of yarns 8 to be warped, this fleece 8 passing between the comb of the creel and the first tension bar 9 of the warping frame which latter may be of any convenient type 85 which ensures a high speed of warping. 80

The comb of the warping frame is arranged in a manner to be approximately on the longitudinal axis of the half cylinder which forms the support 1 with its spindles 90 5. It is therefore approximately at an equal distance between the two extreme ends 2 and 3 of the part 1, and thus equidistant from any point of the inner surface of the cylindrical part 1. The comb is provided 95 with dents 10 fitted vertically on its upper edge, the body 11 thereof being preferably circular in section, to lessen friction between itself and the yarns 7 which pass over it from the cops 5 and through the dents 10 to form, 100 after their passage though the said dents, the fleece 8 to be wound on the beam.

The comb may be mounted at the centre of the half cylinder in any appropriate manner, as for instance by end supports 12 fixed to 105 the inner face of the half cylinder 1, with intermediary supports if desired.

By these arrangements and the charac-

teristic combination of the elements of a creel it will be noted that: (a) the greater part of the length of the fleece of yarns 8, occupies a space above the surface occupied by the creel itself, which permits of the placing of the warping frame nearer to the creel, thus saving space. (b) The length of the yarns 7, between the point where they leave their respective cops 6 and where they enter the dents of the comb 11, is practically always equal for all the yarns being unwound, thus ensuring a constant and uniform tension on all the yarns throughout the unwinding operation. This allows of warping 15 at a high speed, the total length of the yarns 7—8 being practically the same from each cop up to the point of winding on the beam. (c) The axes of each of the cops 6 mounted on their spindles 5, being situated on radii of the cylinder 1 are prolonged into the axis of the said half cylinder; thus the yarns 7, unwinding practically on a line parallel with the said radii, present the minimum of resistance to unwinding, the result being a 25 great decrease in the proportion of broken yarn ends. (d) The side 2 being below the level of the cylinder axis, and thus below the comb 10—11, the fleece of yarns 8 is a little inclined thus allowing the warper to tie up 30 broken ends easily.

Following the principle of the invention, as shown diagrammatically in the Figures 1 and 2, a detailed method of carrying it out is given in Figure 3, according to which it 35 will be seen that the half cylinder 1 is mounted in a form of casing 13, and that the cops 6 may be grouped together in twos or threes, or in greater numbers, around bars 14 the axes of which are, like those of the spindles 40 5, coincident with radii of the half cylinder 1. The bars 14 each carry at their ends the cross bars 15, each supporting two, three or more yarn guides 16, through which the 45 yarn from the cops 6, still maintaining their line parallel with radii of the half cylinder, pass towards the comb 10—11 to form the fleece 8 to be warped.

These yarn guides 16 serve to obviate an excess of ballooning of the yarns 7, a slight 50 resistance to the unwinding of the bobbins

being set up by the yarn 7 from each cop being wound once around the bar 15 as shown in Figure 5.

It will be understood that, for the practical carrying out of the invention, changes, 55 modifications and improvements in the details may be made, in the type of spindles used, in the form of the cops 6, of the yarn guides 14—15—16; of the support 12 of the comb 10—11; and of the comb itself; as well 60 in the nature, dimensions and method of construction of the support 1, without departing from the principle of the said invention.

For example, the central comb 10—11 65 might be replaced by a bar bearing yarn guides, with or without a stop motion.

In certain cases the invention may be applied to the warping of bobbins flanged 70 warpers' bobbins, braking means being provided, in this case, for each end of yarn.

What I claim, is:

1. A creel for the reception of warp cops and other forms of wound yarn to be warped upon a beam or the like, said creel comprising a semi-cylindrical casing, cop spindles arranged on the inner face thereof, the axes of the spindles coinciding with radii of the half cylinder, and a comb situated at the centre of the half cylinder through which 75 all the yarns from the cops or the like must pass to the warping frame.

2. In a creel having the features claimed in claim 1, yarn guides situated near the ends of the cops or the like to guide the yarn to 85 the comb and prevent ballooning, whilst allowing the yarn being unwound from the cops or the like to pass parallel to radii of the half cylinder forming the creel.

3. A creel as claimed in claim 1, having 90 the edge of the casing nearer to the warping frame lower than the half cylinder axis, for the purpose set forth.

In testimony whereof I affix my signature, in presence of two witnesses.

GASTON JOURDAIN.
